US0D1048419S

(12) **United States Design Patent** (10) Patent No.: **US D1,048,419 S**
Jiang (45) Date of Patent: ** Oct. 22, 2024

(54) **THERAPY DEVICE FOR SHOULDER AND KNEE**

(71) Applicant: **Ji Jiang**, Guangdong (CN)

(72) Inventor: **Ji Jiang**, Guangdong (CN)

(*) Notice: Patent file contains an affidavit/declaration under 37 CFR 1.130(b).

(**) Term: **15 Years**

(21) Appl. No.: **29/925,842**

(22) Filed: **Jan. 26, 2024**

(51) LOC (14) Cl. **24-01**

(52) U.S. Cl.

USPC **D24/190**

(58) **Field of Classification Search**

USPC D9/188-192, 200, 206

CPC A61F 5/00; A61F 5/37

See application file for complete search history.

Primary Examiner — Darcey E Gottschalk

(57) **CLAIM**

The ornamental design for a therapy device for shoulder and knee, as shown and described.

DESCRIPTION

FIG. 1 is a front, top perspective view of a therapy device for shoulder and knee, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the therapy device for shoulder and knee that form no part of the claimed design.

1 Claim, 8 Drawing Sheets
